UNITED STATES PATENT OFFICE.

MADISON A. GLENTZER, OF MASSILLON, OHIO.

DESIGN FOR A FLOWER OR SHRUBBERY SUPPORT.

SPECIFICATION forming part of Design No. 35,474, dated December 24, 1901.

Application filed November 18, 1901. Serial No. 82,801. Term of patent 14 years.

To all whom it may concern:

Be it known that I, MADISON A. GLENTZER, a citizen of the United States, residing at Massillon, in the county of Stark and State of Ohio, have invented and produced a certain new and original Design for Flower or Shrubbery Supports; and I do declare the following to be a full, clear, and exact description of the invention, such as will enable others skilled in the art to which it appertains to make and use the same.

The invention relates to a new and original design for a flower or shrubbery support; and it consists of the design of the configuration shown in the accompanying drawings, in which—

Figure 1 is a front view, and Fig. 2 is a side elevation.

The leading feature of the design comprises a rectangular frame 1, each side piece 2 of which is angular in form, and a rectangular

frame 3 of less height than the rectangular frame 2 and diverging downwardly from the side pieces of the rectangular frame 1 from about the central or middle portions of said side pieces, and a netting or open-work material supported by said frame.

This device is specially designed for the cultivation of carnations, roses, chrysanthemums, and, in fact, many other species of flowers and also for shrubbery in general.

What I claim is—

The design for a flower or shrubbery support, as herein shown and described.

In testimony whereof I have hereunto set my hand in presence of two subscribing witnesses.

M. A. GLENTZER.
